Des. 219,613
Patented Dec. 29, 1970

219,613

CASSEROLE DISH OR THE LIKE

Robert R. Gibson, Reisterstown, Md., assignor to Corning Glass Works, Corning, N.Y., a corporation of New York

Filed Nov. 24, 1969, Ser. No. 20,237

Term of patent 14 years

Int. Cl. D7—01
U.S. Cl. D44—15

Fig. 1

Fig. 2

Fig. 3

FIG. 1 is a top plan view of a casserole dish or the like showing my new design.

FIG. 2 is a front elevational view.

FIG. 3 is a side elevational view.

The characteristic feature of the design resides in the particular ornamentation applied to the outer walls.

I claim:

The ornamental design for a casserole dish or the like, as shown and described.
